NECKTIE CLASP

Filed Aug. 11, 1930

Inventor:
Fred G. Herweg,
By: *Albert W. Wilson*
Lilly

UNITED STATES PATENT OFFICE

FRED G. HERWEG, OF CHICAGO, ILLINOIS

NECKTIE CLASP

Application filed August 11, 1930. Serial No. 474,507.

This invention relates to improvements in necktie clasps and it consists of the matters hereinafter described and more particularly pointed out in the appended claims.

- 5 The object of the invention is to provide a device by means of which an associated necktie may be readily positioned with respect to a collar and may be as readily removed therefrom when desired.
- 10 A further object of the invention is to provide a device of the kind which may be embodied in a ready tied tie of either a bow or four-in-hand variety in the manufacture thereof or may be so formed as to be attached 18 to the same after the manufacture thereof whereby any one may apply such a device to a favored tie.

Another object of the invention is to provide a device of this kind which will support 20 a tie in the desired relation with respect to an associated collar of either the stiff or relatively soft type, without lateral tipping and without possibility of its accidental displacement from the collar button.

25 Still a further object of the invention is to provide a device of this kind which includes a tie support having a laterally opening hook with which is associated a spring locking finger, to permit the easy attachment and removal of the tie to or from the front collar button.

These objects of the invention together with others, as well as many advantages thereof will more fully appear as I proceed 35 with my specification.

In the drawings:—

Fig. 1 is a perspective view of a bow tie embodying my improved clasp as when in place upon an associated collar.

40 Fig. 2 is a view in rear elevation on an enlarged scale of the bow tie of Fig. 1 as the same appears when removed from its position of use on the collar.

45 Fig. 3 is a vertical sectional view through a necktie embodying my invention, and associated parts of a shirt and collar, on an enlarged scale as taken on the line 3—3 of Fig. 1.

50 Fig. 4 is a view in rear elevation of a de-

vice embodying my invention as when applied to a ready tied four-in-hand tie.

Fig. 5 is a view in elevation of a blank from which the support of a device shown in Fig. 2 is made.

Fig. 6 is a view in elevation on an enlarged scale of a certain piece of wire embodied in my improved clasp and which will be more fully referred to later.

55 In general my improved device consists of a supporting plate adapted to be secured to the rear side of a ready tied necktie so as to be concealed thereby, which plate includes a rearwardly spaced laterally opening hook, the plate and hook being so formed as to 60 carry a spring finger normally closing the hook, the finger yielding laterally to permit the shank of a collar button to pass into and out of the hook as the necktie is positioned and removed from an associated collar.

65 Referring now in detail to that embodiment of the invention illustrated in Figs. 1, 2 and 3 respectively of the accompanying drawings, 1 indicates as a whole a ready tied bow tie including a central knot 2 and lateral 70 wings 3—3. With such a tie is associated a supporting plate 4 and this plate is preferably curved longitudinally in a manner conforming to the front portion of a collar 5. Such a plate includes a central body portion 75 6 and relatively long lateral extensions or wings 7—7, the body portion having openings 8 therein whereby the said plate may be stitched as at 9 to the rear side of the knot 2 of the tie. When such a plate is secured to a 80 bow tie 1, the wings which decrease in depth or width toward their ends are effectively concealed from view from the front.

85 Along the edges of the wings are provided openings 8^a whereby a covering of the same 90 material as the tie may be stitched in place on the plate, should it so be desired to cover said plate.

95 At the top edge and centrally of the body portion of the plate is formed a slit tongue 10 and at the bottom edge of said body portion but spaced to the rear thereof is a hook 11 having an enlarged central opening 12 and a restricted inlet 13 opening laterally through one side of the hook. Between the 100

plate and hook and arranged more closely to the hook is located a spring finger 14 that normally but yieldingly closes the lateral inlet opening 13. This finger which is made from one end of a length of spring wire as shown on an enlarged scale in Fig. 6 passes through spaced openings 15-15 at the bottom of the hook, the other end of said length of wire entering behind the tongue 10 so that the wire as a whole is effectively held in place upon the supporting plate. Preferably that end of the length of wire forming the finger projects slightly above the top of the hook and is turned laterally outward (in the direction of the opening 13) to form an eye or loop 16.

When the supporting plate, hook and finger as before described are in position upon a bow tie, to apply the tie in place to a collar 5 is a simple matter. Assume therefore, that the collar 5 is a fold-over one and is attached to the neck band portions 17 of a shirt 18 by the usual front collar button which includes a base 19, shank 20 and head 21. With the knot of the tie grasped between the thumb and index finger of one hand with the supporting plate facing the collar, it is only necessary to position the top of the hook 11 against the shank of the button just behind the head. This is an easy matter to accomplish because the finger 14 acts as a guide. When thus engaged, a slight upward movement of the tie will cause the shank of the button to engage the spring finger which yields laterally so that the shank is guided into the lateral inlet 13 of the hook and then snaps into the central opening 12 therein. So soon as the shank slips through the lateral inlet of the hook, the spring finger 14 returns to normal position to close said opening and the supporting plate is thus attached to the button. The corner flaps of the outer fold of the collar are then turned up and the wings or lateral ends of the supporting plate are positioned beneath the same and then said flaps are turned down again with the tie to the outside thereof as shown in Fig. 1.

As the wings of the supporting plate are relatively long, they substantially engage with the fold of the collar and act to hold the tie against lateral tipping. Thus said wings are concealed under the outer flaps of the collar and the tie is held in place to give that neat appearance so desired in ties of this kind.

To remove such a tie it is only necessary to move the tie laterally in the direction of the inlet 13 until the shank of the button engages the spring finger and causes it to yield laterally to free the shank from said inlet. This releases the connection between the supporting plate and collar button after which the tie can then be readily separated from the collar.

In Fig. 4 I have shown the device as applied to a ready tied four-in-hand tie 22 in-

cluding a knot 23 and a skirt 24. Such a tie generally includes lateral wings 25 in the knot thereof for engagement under the front parts of the collar, which knot is usually of a substantial proportion. When a clasp embodying my invention is employed with such a tie, it is apparent that it is unnecessary to employ relatively long wings in the supporting plate. Therefore, I provide a supporting plate 4^a having relatively short wings 7^a-7^a which are concealed by the knot of such a tie. In all other respects, the hook and spring finger employed in the structure shown in Fig. 4 is the same as before described so that in Fig. 4, such parts are indicated by the same reference numerals as before.

In Fig. 5 I have shown the blank from which the supporting plate 4 is made. In such a blank the hook 11 is made as an extension of the bottom edge of the central portion of the plate and it is only necessary to bend it back over in spaced relation but not in engagement with the central body portion of the plate.

The device described may be made and sold at indeed a small price. When associated with a tie, it effectively holds the tie in place to give that neat and trim appearance desired in neckties. Again, a tie having a clasp as described may be quickly and easily positioned and removed from an associated collar.

While in describing the invention, I have referred in detail to the form, arrangement and construction of the parts thereof, the same is to be considered as illustrative only so that I do not wish to be limited thereto except as may be specifically set forth in the appended claims.

I claim as my invention:—

1. In combination with a necktie having a knot, a supporting plate attached to the rear side of the knot and including a rearwardly spaced hook having an opening therein with an inlet that opens through one side of the hook and a spring finger carried by the plate and normally operating to close the inlet of said opening in said hook and having a part extending above the top of the hook adapted for engagement with a collar button to guide it into said inlet of said opening.

2. In combination with a necktie having a knot, a supporting plate attached to the rear side of the knot and including a rearwardly spaced hook having an opening therein with an inlet that opens through one side of the hook and a spring finger carried by the plate and normally operating to close the inlet of said opening in said hook, said finger extending above the top of the hook to be engaged by a collar button for directing the same into the inlet of said opening in said hook.

3. A tie clasp comprising a supporting plate including a central body portion and side portions forming wings for the plate,

said plate including an integral turned back hook at the bottom of the body portion which hook has a side inlet and a length of wire engaged with said body portion and including 5 a part associated with the inlet to form a yielding finger normally closing the same, said part of said length of wire extending above the top of the hook to be engaged by a collar button for guiding the same into said 10 inlet.

4. A tie clasp comprising a supporting plate including a central body portion and side portions forming wings for the plate, said plate including an integral turned back 15 hook at the bottom of the body portion which hook has a side inlet and a length of wire having its mid portion passing through said body portion with one end anchored to the top of said body portion and with its other 20 and free end formed to provide a yieldable finger normally closing off said side inlet.

5. In a necktie clasp, a supporting plate including a central body portion and lateral wing portions, the top of the body portion 25 being formed to provide a tongue and the bottom of the body portion having a hook bent back upon but spaced rearwardly from said body portion, the hook having an inlet in one side, said tongue being adapted to se- 30 cure one end of a yielding finger member engaged with the bottom of said body portion and including another end that extends across said inlet.

In testimony whereof, I have hereunto set 35 my hand, this 2nd day of August, 1930.

FRED G. HERWEG.
